SOUND HEAD FOR REPRODUCING SOUND
FROM SOUND FILMS

David Percival Fisher, Wellington, New Zealand

Application July 26, 1934, Serial No. 737,104
In New Zealand July 31, 1933

5 Claims. (Cl. 271—2.3)

This invention relates to cinematograph and sound projecting machines, and particularly to that portion of the machine for reproducing the sound from a sound film.

5 The chief object of the invention is to obviate or reduce the fluctuation of the film during its passage through the sound gate.

According to my invention, I provide a fly wheel drum on which the film runs after it leaves the intermittent sprocket of the projector, and also a roller having means to prevent sudden variations of speed thereof, such roller placed at a position just before the entrance of the light aperture, usually termed the "sound gate". This arrangement provides (1) that the flutter or vibration of the film as it leaves the intermittent sprocket will be damped or arrested as the film passes over the fly wheel drum, and (2) that the film will be prevented from sudden variations of speed as it passes through the "sound gate" by means of the roller referred to.

I provide also a device consisting of a pulley mounted by means of a spring upon a weighted pendulum which is pivoted so as to be free to swing or oscillate so as to retain the film at an even tautness and enable fluctuation in the speed of the film due to irregularities in the driving sprocket or other parts of the mechanism of the machine to be taken up in the loop between the guide roller and the take-up sprocket.

The invention will be described with the aid of the accompanying drawings, wherein:—

Figure 1 is an elevation of the invention.

Figure 2 is a plan.

Figure 3 is an end view.

Figure 4 is a front elevation of the pulley device, and

Figure 5 is a side elevation thereof.

40 Figure 6 is a diagram showing the operation of the pulley device.

Figure 7 is an obverse view of the drum showing how it is mounted, but drawn to a larger scale.

45 Figure 8 is a cross sectional elevation on line A—A Figure 7.

Referring to the drawings, the apparatus consists of the usual parts of a sound head, namely casing or frame 1, photo-cell 3, optical system 4, sound gate 5, take-up sprocket 6, and guide roller 7, the film 8 leading from the intermittent sprocket 9 of the projector apparatus.

In this invention, a steadyng roller 2 with or without sprocket teeth, the one illustrated 55 having sprocket teeth, is placed at a position

close to the leading-in side of the sound gate 5, and has a fly wheel 11 upon its spindle for the purpose of preventing any sudden variation in the speed of the sprocket. The usual practice is to place a sprocket below the "sound gate", in 5 which case it must be driven by other means than the film. In this invention, the sprocket 2 is not in any way equivalent to a sprocket placed on the leading-out side of the sound gate. The sprocket 2 is not for the purpose of drawing the film but to enable the fly wheel to be rotated for steadyng the speed of the sprocket, so that a smooth roller in place of a sprocketed roller may be preferable in some cases.

At a suitable position from the intermittent 15 sprocket 9, so as to form a loop A in the film, there is placed a heavy fly wheel drum 10 which is adjustably mounted, as will hereinafter be described, and over which the film 8 passes. It has a recessed portion in the centre so that the 20 centre of the film does not contact with the drum. The film is given the required peripheral contact with the drum by a roller 19 mounted, as will be hereinafter explained. By so positioning the drum 10, the flutter tending to occur 25 in the film 8 after it leaves the intermittent sprocket 9, will be damped by reason of the heavy fly wheel drum 10, and the film will then pass in a fairly steady condition to the sprocket 2, which will complete the steadyng effect, so that 30 the film will be completely steady as it passes through the sound gate. The film, after it leaves the sound gate 5, passes over the guide roller 7 and thence over a pulley 12 which is mounted by 35 means of a spring 13 upon a weighted pendulum 14 pivoted on a pin 15 fixed in the frame 1 so as to be free to swing or oscillate according to variations of the pull due to varying speeds or inaccuracies of the take-up sprocket.

The pulley 12 consists of two independent 40 pulleys spaced apart so that the edge of the film will be carried by them (see Figures 3, 4 and 5). It will be seen, therefore, that by disposition of the sprocket 2 and fly wheel drum 10, the film would lead from the usual intermittent projector 45 sprocket 9, over the fly wheel drum 10, and over the sprocket 2 against which it is retained by a suitable guide pulley 17 and thence through the sound gate to and around the guide roller 7 and thence over the spring mounted pulley 12, and 50 thence to the take-up sprocket 6.

Should any variation of speed in the film take place between the sprocket 2 and the take-up sprocket 6, it is immediately corrected by means of the pulley 12, for example, if the portion of 55

the film between the sprocket 2 and the take-up sprocket is tended to increase in speed, the pulley moves to the position shown in dotted lines in Figure 6. Any decrease in speed or slackness of the film which may occur between the guide roller and the take-up sprocket 6 is prevented from being transmitted back to that portion of the film passing through the sound gate by the pulley 12 moving back to the position shown in full lines in Figure 6.

The fly wheel drum 10 is rotatably mounted on a pin 20 fixed in an arm 21 through which a pin 22 is screwed into the casing 1 and secures the arm in a selected position. The roller 19 is pivoted freely on a spindle 23 projecting from an arm 24 fixed on a pin 25 entering a boss 26 of an arm 27 pivoted on a boss 28 of the arm 21. The pin 25 is reduced and has a coil spring 29 around it and attached at one end to the pin 25 and its other end attached to a cap 30 fitting within the boss 26 and secured on the pin by a screw 31. The cap 30 can, therefore, rotate on the pin 25, and the tension of the spring can thus be adjusted, the cap 30 being secured by a set screw 32. Thus, the required tension can be given to the roller 19. The arm 27 can also be adjusted on the boss 28 of the arm 21 and secured thereon by a set pin 33 passing through the end of the arm which is in the form of a split boss.

A set screw 34 secures the pin 20 in the arm 21. The set screws 32 and 34 are indicated in dotted lines in Figure 8, but the actual position of them would be as shown in Figure 7.

35 By slackening the set screw 22 and adjusting the position of the arm 21, the drum 10 may be placed closer or further from the intermittent sprocket 9 so as to obtain the best position in each case. The alternating of the position of the drum would cause the roller 19 to lie either nearer the top of the drum or more towards the lower part thereof, but by slackening the screw 33 the arm can be rotated on the boss 28 and the roller 19 thereby adjusted to the best position in relation to the drum.

The roller or sprocket 2, instead of having a fly wheel, may have any other equivalent means for steadyng its speed.

What I claim is:—

50 1. Means for regulating the motion of a film after it has passed through a sound gate, consisting of a pulley, a spring on the upper end of which said pulley is rotatably mounted, a pendulum weight pivoted on an axis parallel with that of the pulley so as to swing from such axis, said

spring having its lower end attached to said pendulum weight.

2. Means for regulating the motion of a film in passing through a sound gate, in combination, a sprocketed roller over which the film passes, 5 said sprocket roller driven by the film and located immediately before the entrance of the sound gate, inertia means on the spindle of said sprocket roller, a guide pulley over which the film passes supported beyond the sound gate, a 10 spring pulley, a weighted pendulum on which said pulley is mounted in order to prevent variations in the film beyond the sound gate affecting that portion of the film between the sprocket roller and the guide pulley. 15

3. In the device as claimed in claim 2, said spring guide pulley having a spring secured to the pendulum and carrying at its upper end the said pulley.

4. In a cinematograph and sound projecting 20 machines in which the film after it leaves the intermittent sprocket of the projector passes through a sound gate, a frame, a fly-wheel drum for dampening irregular motion in the film, an arm adjustably attached to said frame and means for holding said arm in adjusted position, said fly-wheel drum being mounted on said arm, and means for holding the film in contact with the periphery of the spring drum comprising, a second arm pivotally mounted on the axle of said 30 fly-wheel drum, means for holding said second arm in adjusted position, and a third arm pivoted on said second arm, a roller mounted in said third arm and spring means for pressing said third arm into contact with the periphery of said 35 fly-wheel drum.

5. In dampening means for removing fluctuating and irregular motion in a film on its path to the sound gate, a frame, an arm adjustably attached to said frame, means for holding said arm in an adjusted position, and a cylindrical 40 self-contained flywheel drum freely mounted on said arm to rotate on its own axis, said drum of large diameter to provide a large circumferential contact of the film with the drum as the film 45 passes over the circumferential periphery and thus damp the movement through a considerable length of the film, the mass of said drum being such that the drum itself will provide the required inertia and momentum to remain steady 50 during its rotation and means for pressing the film against the periphery of the drum to give sufficient length of contact and friction between the film and the drum to rotate said drum.

DAVID P. FISHER.
